To all whom it may concern:

Be it known that I, EMIL STEFFENS, a citizen of the United States, and a resident of New York city, in the county of New York and State of New York, have invented a certain new and original Ornamental Pattern for Cigar-Boxes, &c., of which the following is a specification.

The design shown in the accompanying drawing, forming part hereof, comprises a central panel of elliptical shape surrounded by decorative work, which, at the ends of the panel, includes circular devices or medals.

At the corners and ends, and between the border and the decorative work surrounding the panel, the design includes flowered and scroll work.

The design is to be placed on the lids of cigar-boxes.
